CONVERTIBLE FURNITURE

Bernard Finer, New York, N. Y.

Application July 2, 1946, Serial No. 681,018

1. Claim. (Cl. 155—46)

1
The invention relates to a piece of furniture which is convertible either into an armchair or into a bed.

Various suggestions have been made to solve this problem, but the constructions designed for this purpose are complicated and costly.

It is a primary object of the invention to effect the conversion of an armchair into a bed and vice versa by the exercise of the simple expedient of swinging the side rests of the furniture into the upright or into the horizontal position.

It is another object of the invention to cause the side rests of the furniture to drop by gravity automatically into the horizontal bed forming position.

It is also an object of the invention to limit the automatic drop of the side rests into the bed forming position by the shape of the side rests.

Further objects and advantages of the invention will become apparent as this specification proceeds.

The invention is by way of example illustrated in the attached drawings.

In the drawings

Fig. 1 is a front elevation and a part section on line 1—1 of Fig. 2 showing the furniture frame embodied in this invention for use as an armchair.

Fig. 2 is a top view of the frame shown in Fig. 1.

Fig. 3 is a side elevation of the frame structure shown in Fig. 1 upon conversion of the arm chair into a bed.

Fig. 4 is an enlarged view of the locking mechanism for the side rests, and

Fig. 5 is a section on line 5—5 in Fig. 4.

The frame of the convertible furniture shown in the drawings is composed of two vertical rear posts 3 and two preferably shorter vertical front posts 4; these posts forming the corners of a quadrangular structure are in the usual manner connected by several horizontal transverse braces 1, 2; the posts and braces 1, 2, 3, 4 form the main or center part of the furniture frame.

This frame carries two side or arm rests 5 which are hingedly connected with the same at 6; the side rests have at the upper end out-flaring portions 27.

The frame is covered by upholstering in the usual manner to form the finished article.

If the side rests 5 are in the upright position shown in Fig. 1, the furniture serves as an armchair; when the side rests 5 are swung down in the direction of arrows 7 the furniture serves as a bed, the upper reclining plane of which will

then be composed of the upholstered seat of the armchair and the upholstered upper faces of the swung-down side rests 5, as for instance shown in my prior patent application Ser. No. 656,429.

This invention is specifically concerned with the provision of means to lock the side rests 5 automatically in their upright or armchair forming position and to unlock or release both side rests simultaneously by the use of one common expedient, whereupon they will drop by gravity automatically into the horizontal or bed forming position.

In order to lock the side rests 5 in the upright position, shown in Fig. 1, hooks 8 are provided which are fastened to the side rests 5; these hooks are adapted to engage the locking rods or plates 9 which are located for vertical displacement in the recesses 10 of posts 3, the recesses ending short of the upper end of the posts. The plate 9 carries at its lower end a small disc 11; a short rod 12 is connected with this disc and a wire or chain 13 is attached to the lower end of rod 12 by means of a hook or any other appropriate means.

25 A bracket 15, see Figs. 1 and 4 is fastened to the recessed posts 3 in such a manner as to guide the disc 11 during the vertical displacement of the rod or plate 9. An aperture 14 is provided in the horizontal base portion 28 of bracket 15 in such a manner that the rod 12 may pass through this aperture; a spring 16 surrounds the rod 12 and abuts with its upper end against disc 11 and with its lower end against the base portion 28 of the bracket 15.

35 If the locking plate or rod 9 is downwardly pulled, as later explained, it slides along the vertical portion of bracket 15 the spring 16 being at the same time compressed between disc 11 and the base portion 28 of the bracket.

40 The upper end portion of plate or rod 9 is inwardly bent to facilitate the gliding of hook 8 along the upper end of the rod when the side rests 5 are turned upwards for conversion of the furniture into an armchair; by the arrival of hooks 8 in the locking position spring 16 is compressed.

A wire 13 running over a pulley 17, carried by a bracket 18, is attached to the lower end of the rod 12. The wire 13 runs from this pulley through a bore 19 in block 20 attached to a lower brace of the frame; the end of the wire 13 is attached to the one arm of a double arm lever 21. This lever 21 is mounted on a shaft 22 journalled in the lower braces of the frame.

An analogous mechanism as above described is provided for the other vertical rear post 3 with

the only exception that the end of the wire 13 is here attached to the other arm of the two-armed lever 21.

The shaft 22 projects at the rear side of the frame, see Fig. 2, and carries at its end a lever 23 which is attached to a foot pedal 24.

The mechanism is secured in the position shown in Figs. 1 and 2 by a spring 25 attached to the upper end of lever 21 and to a stud 26 secured to the block 20.

In order to convert the armchair into a bed, the pedal 24 is pressed down, turning thereby shaft 22 in counterclockwise direction. The lever 21 being turned in the same direction against the action of spring 25 exerts simultaneously a down-pull on both wires 13; the plate or rod 9 is pulled downwards against the action of spring 16 which at the same time is compressed between disc 11 and bracket 15; the locking action produced by the cooperation of rod 9 and hook 8 is thereby released. The hooks 8 being brought out of engagement with the rods or plates 9 allow the arm rests 5 to swing down by gravity whereby the arm chair is converted into a bed.

In order to reconvert the bed into an arm chair the side rests 5 are turned upwards until the hooks 8 strike the rods or plates 9.

In continuing this movement the ends of the hooks 8 slide along the inclined part of rods 9, pressing the same down against the action of spring 16 until rods 9 enter into locking engagement with hooks 8 under the action of the expanding spring 16; the arm rest 5 is now again locked in the upright position shown in Figs. 1 and 5.

Various changes and modifications may be made to the details of construction of the invention without departing from the broader spirit and scope thereof, as set forth in the following claim.

I claim:

A piece of furniture adapted to be converted into an armchair or into a bed, comprising a main frame composed of two vertical rear and two

vertical front posts, braces connecting the said posts, two side rests having outflaring portions at the upper end hingedly connected with a pair of said posts consisting of one front and one rear post, said side rests being adapted to be swung from the upright position adjacent to said posts into a horizontal position and to be supported in this position by said outflaring portions and further adapted to be reswung into the upright position, vertical recesses in said rear posts, means in said recesses to automatically lock said side rests in the upright position adjacent to said vertical posts, said means including hooks connected to said side rests, vertically displaceable locking rods to engage said hooks, two pulling wires fastened to said rods, two springs surrounding said rods and fastened to said posts to be compressed by the downward displacement of said rods, a shaft journaled in said frame, a double arm lever carried by said shaft, the ends of said lever being connected with said two pulling wires, and a foot pedal to rotate said shaft and to thereby pull said rods out of engagement with said hooks and to release said side rests for a down-swing exercised by the weight of said outflaring portions.

BERNARD FINER.
